UNITED STATES PATENT OFFICE.

PAUL O. E. FRIEDRICH, OF NEW YORK, N. Y., ASSIGNOR TO CALORIS MANUFACTURING COMPANY, A CORPORATION OF DELAWARE.

DESIGN FOR A BOTTLE.

No. 39,477.

Specification for Design.

Patented Sept. 1, 1908.

Application filed July 1, 1908. Serial No. 441,512. Term of patent 7 years.

To all whom it may concern:

Be it known that I, PAUL O. E. FRIEDRICH, a citizen of the United States, residing at New York city, county of New York, State of New York, have invented a new, original, and ornamental Design for Vacuum-Bottles, of which the following is a specification, reference being had to the accompanying drawing, forming part thereof.

My new, original and ornamental design

for a bottle is shown in the accompanying drawing, in which the figure is a perspective view of a bottle.

I claim:—

The ornamental design for a bottle, as shown.

PAUL O. E. FRIEDRICH.
